FIG. 3.

Richard Oliver,

Attorney

UNITED STATES PATENT OFFICE.

CHARLES R. POWELL, OF NEW YORK, N. Y.

BRAKE-SHOE.

1,369,836.

Specification of Letters Patent.

Patented Mar. 1, 1921.

Application filed December 2, 1918. Serial No. 265,010.

To all whom it may concern:

Be it known that I, CHARLES R. POWELL, a citizen of the United States, residing at New York, in the county of New York and 5 State of New York, have invented certain new and useful Improvements in Brake-Shoes, of which the following is a specification.

This invention has relation to railway 10 brake appliances, with particular reference to brake shoes and heads, and has for an object to provide means to be formed upon the shoe to bend and deflect the key which is employed to hold the shoe and head together, in such a manner as to prevent the 15 accidental or casual dislodgment of the key in use.

Another object of the invention is to provide an improved brake shoe having one or 20 more deflecting lugs of specific formation and located in a specific manner, for accomplishing the purpose above set forth.

Another object of the invention is to provide a deflecting lug in a brake shoe designed to cause the brake head to initially 25 move away from the shoe when the key is first driven and to impart a slight curvature to the latter, and whereby the act of applying the brakes will result in the further 30 bending of the key to the proper extent to securely lock the shoe and head against separation, to prevent disengagement of the brake hanger and to prevent casual dislodgment of the key.

35 In addition to the foregoing this invention comprehends improvements in the details of construction and arrangement of parts to be hereinafter set forth and specifically pointed out in the appended claims.

40 In the accompanying drawing in which similar and corresponding parts are designated by same characters of reference throughout the several views in which they appear;

45 Figure 1 is a view in side elevation of the brake shoe and head during the insertion of the key and before the latter is bent.

Fig. 2— is a similar view with the key deflected after the application of the brakes, 50 and

Fig. 3— is a view of a modified form of brake shoe.

In railway practice it is a well recognized fault of brake head and shoe design 55 that the key which is used to hold the head and shoe together is prone to become acci-

dentially dislodged, and is readily subject to removal by unauthorized persons. The key may fall from its normal position and thus permit the hanger to become disengaged 60 from the head, the brake beam as a result falling upon the tracks and perhaps causing derailment of the train. I am aware that other attempts have been made to remedy this trouble by deflecting the key and my invention 65 therefore consists in a new means for deflecting the key which depends for its novelty in the location of the means so as to impart a specific curvature to the key.

Proceeding with a description of the device 10 indicates a car wheel, and 11 a brake shoe to engage the same. The brake shoe is formed with upper and lower end lugs 12 and 13 respectively in accordance with standard practice, and an intermediate lug 14 which is apertured to receive a key. A standard brake head 15 is formed with end lugs 16 which engage the lugs 12 and 13 of the shoe when the parts are assembled as shown in the drawings. Intermediate of 70 the head are a pair of apertured, spaced key lugs 17 and 18 which receive therebetween the lug 14 of the shoe. The apertures of the lugs 14, 17 and 18 should aline to freely receive the key which is indicated at 19 and 75 which is normally in the form of a slightly curved and headed strip, the head being indicated at 20. The brake hanger shown at 80 21 enters a recess 22 formed in the head to receive the brake hanger. My invention 85 includes the provision of a lug 23 on the outer or convex side of the brake shoe. The upper side of the lug 23 extends outwardly at an acute angle relative to the convex side of the brake shoe downwardly forming an 90 elliptical curve 25. The juncture of the surface 25 with the convex side of the brake shoe should be sufficiently spaced from the lug 14 as to snugly receive therebetween the lower lug 18 of the brake head. The size of 95 the lug 14 may vary in practice, and it is not intended that the design thereof as here described be construed as an absolutely essential part of the present invention.

In use the key 19 is inserted point first 100 into the upper end of the brake head, or through the lug 16 thereof, and then through the lugs 17, 14 and 18 in the order named. The point will be bent or deflected slightly toward the brake head, riding over 105 the curved end of the lug 23 until the point of the key comes to rest and engages the in-

ner surface of the brake head, at the point 26, whereupon it is driven downward by means of a hammer until the key comes to rest in the position shown in Fig. 1. During this operation the lower end of the 10 brake head will be moved away from the brake shoe to some extent. The parts will remain in this relation until the first application of the brakes. The movement of the lower end of the head toward the shoe which will be produced by such application will result in a further bending of the key, the lug 23 forming a short bend in the key at *a*. The intermediate portion of the key 15 will be bent to arcuate formation as at *b* and the key will assume the configuration shown in Fig. 2.

I am aware that it is old in the art to provide abutments of various kinds to deflect 20 keys in brake head and shoe assemblies, as in the Fahrenbruch Patent No. 1,247,652, but I am not aware that a lug has ever been applied to a brake shoe for this purpose. It will be noted from Fig. 2 that the key, owing 25 to the bend at the point *a*, cannot be withdrawn except by means of a tool and with the application of great effort. It will also be obvious that in the event that the brake shoe should become disengaged from the brake 30 head by reason of the fracture of the lug 14 which is sometimes the case, the key could not fall from the brake head, even if the head 20 of the key was broken off or straightened out. This is because of the peculiar 35 curvature of the deflected key which would bind at its points of curvature against the sides of the brake head and the apertures of the lugs 17 and 18. Thus, if the key can be held in the head at all times, obviously the 40 brake hanger 21 cannot be disengaged from the recess 22 since the latter is closed by the extension of the key thereacross. Therefore, by placing the lug 23 on the shoe a positive lock is provided to prevent the separation of the head and shoe, as well as an 45 infallible means of preventing disengagement of the head from the hanger. By providing the lug upon the shoe this invention may be quickly embodied in standard rail- 50 way equipment with a minimum of expense, since shoes are replaced more frequently than brake heads. It can also be readily proven

in practice that the key will be gripped tighter when the lug is placed on the shoe in the manner set forth than when on the head 55 as shown in the art.

I have illustrated in Fig. 3 a modified form of my invention in which the brake shoe 11' is provided with a pair of lugs 27 which are located, one at each side of the lug 14 so 60 that the key may be inserted from either end of the shoe, that is the shoe may be reversed when applying it to the brake head. The key, by this method will receive a double deflection which will serve to secure the same 65 even tighter.

While I have illustrated and described my invention with some degree of particularity, I realize that in practice various alterations 70 therein may be made, I therefore reserve the right and privilege of changing the form of the details of construction or otherwise rearranging the relation of the correlated parts, without departing from the spirit of the invention or the scope of the appended 75 claims.

Having thus described my invention, what I claim as new and desire to secure by United States Letters Patent is;

1. In combination with a brake shoe and 80 head, means on the shoe to impart a slight curvature to a key driven between shoe and head whereby the latter are slightly separated, and for imparting a greater deflection when the brakes are initially applied 85 after the insertion of the key.

2. In combination with a brake shoe having 90 an apertured lug and a brake head having a pair of apertured lugs to receive the first lug therebetween, a deflecting lug 95 formed on the shoe and adapted to cause slight separation of the shoe and head when a key is driven therebetween, and to impart an acute bend in the key whereby to prevent longitudinal movement of the key in either direction, with or without the association of the shoe with the head.

In testimony whereof I affix my signature in presence of two witnesses.

CHARLES R. POWELL. [L. s.]
